UNITED STATES PATENT OFFICE.

WILLIAM W. GUEST, OF ALAMEDA, CALIFORNIA, ASSIGNOR TO THE ECLA MINING CORPORATION, A CORPORATION OF ARIZONA.

FLUID-ACTUATED SPRING MECHANISM.

1,178,638.

Specification of Letters Patent. Patented Apr. 11, 1916.

Application filed March 16, 1915. Serial No. 14,710.

To all whom it may concern:

Be it known that I, WILLIAM W. GUEST, a citizen of the United States, residing at Alameda, in the county of Alameda, State 5 of California, have invented a new and useful Fluid-Actuated Spring Mechanism, of which the following is a specification in such full and clear terms as will enable those skilled in the art to construct and use the same.

This invention relates to a fluid spring adapted to take the place of the ordinary metal springs and to dispense with the use of metal either in torsion or bending.

Another object of the invention is to produce a spring capable of being varied in form to increase or diminish the resiliency thereof as may be required for the given work to be done, and which may at the same 20 time be so modified by the use of a high or low pressure therein as may be required to carry heavy or light loads.

Another object of the invention is to provide a spring which will have its movable 25 parts so protected as to prevent the access of grease, dirt and grit thereto, thereby increasing the life of the spring and improving its working qualities.

One of the objects of the invention is to produce a fluid spring which will insure the 30 retention in the device of the air or other gas used for giving the resilient effect.

An embodiment of the invention is shown in the drawing in which the same reference 35 numeral is applied to the same portion throughout, but I am aware that there are many modifications thereof.

Figure 1 is a vertical sectional view thereof, and Fig. 2 is a side elevation of the complete spring.

The spring comprises two cups 1 and 2 connected by means of a coupling 3. The coupling 3 is threaded on the cup 1 and it has an inturned flange 4 which overlies the 45 outwardly turned flange 5 of the cup, thereby holding the two parts together. Each cup has a portion thereof extending inwardly as indicated at 6 and 7 for the purpose of reducing the total volume of air under pressure and the extension 7 is provided with a hole through which the air valve 8 projects, said valve being of a well known type and being connected to the air receptacle 9 which may be made of any desired air 50 or water tight material such as rubber or

the like. The bag 9 has a plurality of outwardly extending ribs 10 which ribs have their inner surfaces closely adjacent the part of the bag covering the extensions 6 and 7. The grooves formed between adjacent ribs 60 are surrounded by rings 12, while the ribs are each covered with a channel ring 13 having its flanges projecting into close proximity to the rings 12. In order to prevent the material of which the gas bag or air bag is 65 made from being abraded by the rings 12 and 13 each ring is covered with a suitably hard and flexible material 15. This spring is intended for compression work and each of the cups 1 and 2 is provided with lugs as 70 indicated at 16, 17, 18 and 19 for connecting the spring casing with any suitable shackle.

It is to be observed that the possible movement is the distance between the flange 5 and the end of the cup 1 opposite it, and it will also be seen that the resilient effect of the spring may be varied either by increasing or diminishing the pressure therein or by changing the total internal volume by producing cups with shallow or deep depressions as may be required for the given work. In other words, if the spring is constructed as shown in the drawing and neglecting the space between the several flanges of the fluid containing sack, which spaces are reduced in 85 size, it will be seen that the pressure in the fluid tube will increase to double its normal pressure if the flange 5 and cup of which it is a part moves one-half the distance toward the cup, while if the volume in the bag is 90 larger by 50% the increase in pressure for the same movement will be correspondingly less.

Having thus described my invention what I claim as new and desire to secure by Letters Patent of the United States, is as follows, modifications within the scope of the claims being expressly reserved:

1. A fluid spring comprising a pair of cups, a coupling for connecting the cups and for permitting one to move with respect to the other, a corrugated gas bag within the cups for holding them resiliently apart, a plurality of rings in the corrugations of said bag for strengthening it, and a plurality of 100 channel bars surrounding each corrugation of the bag.

2. A fluid spring comprising a pair of cups each having a depression in its end, a coupling for connecting one cup to the other 110

and for permitting one cup to move with respect to the other, a corrugated gas bag within the cups for holding them resiliently apart, a ring in each depression of the corrugated gas bag, a plurality of channel rings surrounding the several corrugations of the gas bag, and a valve for permitting the supply of gas to said gas bag.

3. A fluid spring comprising a pair of 10 cups each having a reëntrant portion in its end, a coupling for connecting one cup to the other and for permitting one cup to move with respect to the other, a corrugated gas bag within the cups for holding them re-

silently apart, a ring in each depression of 15 the corrugated gas bag, a plurality of channel rings surrounding the several corrugations of the gas bag, a band surrounding each channel ring, and a valve for admitting 20 the supply of gas to said gas bag.

In testimony whereof I have hereunto set my hand this 9th day of March, 1915, in the presence of the two subscribed witnesses.

WILLIAM W. GUEST.
